COMBINED BOBBY PIN AND HOLDERS FOR ABSORBENT PELLETS FOR PERFUMING

Joan Weiss, 325 E. 77th St., New York, N.Y.

Filed Apr. 17, 1964, Ser. No. 79,553

Term of patent 14 years

(Cl. D86—10)

FIG. 1.

FIG. 2.

The characteristic feature of my design resides in the combination of the linked holders for perfuming to an inverted matching floral member fitted over the closed end of the bobby pin.

I claim:

The ornamental design for a combined bobby pin and holders for absorbent pellets for perfuming, substantially as shown and described.
